UNITED STATES PATENT OFFICE.

HENRI JOLY, OF PARIS, FRANCE.

SYNCHRONIZING APPARATUS.

No. 839,152.

Specification of Letters Patent.

Patented Dec. 25, 1906.

Application filed January 8, 1906. Serial No. 295,145.

To all whom it may concern:

Be it known that I, HENRI JOLY, a citizen of the Republic of France, residing in Paris, France, have invented certain new and useful Improvements in Synchronizing Apparatus, of which the following is a specification.

This invention relates to a synchronizing apparatus intended to coördinate the movements of the driving mechanisms of a phonograph and a kinematograph combined.

When a phonograph and a kinematograph are intended to coöperate, it is necessary for fear of completely altering the sounds to let the phonograph go absolutely freely and regularly. On the contrary, the kinematograph allows of a certain freedom of speed without the eye of the observer noticing the difference of speed—for instance, such as obtained in turning the apparatus by hand.

The synchronizing apparatus forming the subject of this invention is a speed-indicator which enables the speed of the kinematograph to be ascertained at every moment and regulated in accordance with that of the phonograph. This indicator apparatus chiefly consists of two rotating indicator-hands, preferably concentrically arranged, one of which is freely and regularly operated by the phonograph, while the other depends on the movement given to the kinematograph in such manner that the second hand can be made to follow exactly the speed of the first, the speed of the said kinematograph thus being modified. This action can be effected either by hand or by means of a resistance when the kinematograph is operated by a mechanical or electric motor.

In the accompanying drawings, Figure 1 shows diagrammatically the connection of the various apparatus with each other. Fig. 2 is a front view of the synchronizing apparatus according to this invention. Fig. 3 is a back view of the same apparatus, and Fig. 4 a vertical section on line A A of Fig. 3.

The phonograph *a*, which may be a cylinder or disk phonograph, is operated by any desired motor, clockwork, electric, or any other motor. On the spindle *d* of the said phonograph or on an intermediate spindle is mounted a small cam *e* with two bosses co-operating with two flexible insulated plates *f* for closing the circuit of an electric current from any source—battery *p* or any other. The number of interruptions thus produced in the electric circuit is exactly in proportion to the number of revolutions of the phono-

graph. These interruptions act on an electromagnet *g*, arranged in the casing *h* of the indicator apparatus, Figs. 3 and 4.

At each passage of the current the electromagnet *g* attracts the armature *i*, which is provided with a spring *j*, the tension of which can be adjusted. The armature *i* is provided at the end opposite to that at which it is hinged with pawls *k*, which coöperate with a ratchet-wheel *l* in order to cause the latter to be intermittently moved to the extent of one tooth at each attraction and return of the armature *i*.

The ratchet-wheel *l* is mounted on a spindle to which is keyed a pinion *m*, engaging with a toothed wheel *n*, the spindle *o* of which passes through the front plate of the casing *h* and is provided outside the latter with an indicator-hand *r*. The object of the toothed wheel *n* is simply to reduce the speed of the hand *r* so that it can be easily followed by the eyes. Spring-blades *m' n'* rest against the spindles *m* and *n* in order to maintain them during the various movements of the armature *i*.

The dial *q*, in front of which the hand *r* moves, has itself a movement of rotation independent of the said hand. To effect this, the said dial *q* is mounted on a fixed socket *t*, through which the spindle *o* passes, so that it can rotate freely on the said socket *t* concentrically with the spindle *o*. The dial *q* is secured to a wheel *u* with helical teeth engaging with a screw *v*. The spindle of the latter is connected by a flexible or other shaft *c* to one of the spindles of the kinematograph *b*, which is operated by hand by means of the handle *x* or mechanically or electrically, with a resistance capable of being varied as desired. On the dial *q* is made a clearly-visible mark, or there is fixed a hand *s* the point of which is directed toward that of the hand *r*.

On the casing *h* of the indicator is arranged a contact-button *y*, connected to the source of electricity *p*, and an electromagnet *z*, the armature of which acts on the disengaging-lever of the phonograph when the said button *y* is pressed.

A circuit-breaker *w*, consisting of a peg engaging between and connecting two plates *a' b'*, arranged in the path of one of the wires terminating at the electric source *p*, enables the latter to be connected with the electromagnets *g* and *z* when the apparatus is started. This starting is effected in the following manner: First of all, the two hands *r*

and *s* are placed exactly opposite each other by turning the central hand *r* in the direction of the arrow—that is to say, in the direction permitted by the inclination of the teeth of the ratchet-wheel *l*. The peg *w* is then introduced between the plates and the button *y* is pressed in order to disengage the driving mechanism of the phonograph by the electromagnet *z*. The starting of the spindle *d*, carrying the cam *e* with two bosses, results in producing intermittent passage of current through the circuit of the electromagnet *g*, which acts then on the mechanism of the hand *r* in order to rotate the latter with a speed in proportion to that of the phonograph *a*. As soon as the hand *r* has been started the kinematograph is operated so that the movement which it imparts to the dial *q*, carrying the hand *s*, should be exactly the same as that imparted to the hand *r* by the phonograph, which can be easily effected by observing the rhythm of the electromagnet *g* and imparting the same to the motor of the kinematograph.

It is obvious that various detail modifications could be made in this apparatus for synchronizing two movable things caused to move. Thus, for instance, the functions of the dial *q* and of the central hand *r* could be reversed—that is to say, the dial *q* could be

driven by the phonograph and the hand *r* by the kinematograph.

What I claim as my invention, and desire to secure by Letters Patent, is—

In an apparatus for synchronizing a phonograph and a kinematograph the combination of a shaft of the phonograph said shaft working at an approximately uniform speed, an electric-circuit closer comprising two projections mounted on the shaft, two flexible insulated plates, an electromagnet electrically connected to the plates, a pivoted armature, a spring tending to keep the armature out of contact with the electromagnet, a rotatable speed-indicating needle for the phonograph, a mechanism operated to actuate the indicator upon the vibration of the armature, a kinematograph-shaft rotating at variable speeds, a speed-indicating dial mounted concentric with the needle, a needle on the dial, and means for transmitting motion from the kinematograph-shaft to the dial.

In testimony whereof I have signed my name to this specification in the presence of two subscribing witnesses.

HENRI JOLY.
